UNITED STATES PATENT OFFICE.

WALTER J. FROST, OF KENOSHA, WISCONSIN.

DESIGN FOR A TRAP FOR WASTE-WATER PIPES.

No. 39,573.

Specification for Design.

Patented Sept. 22, 1908.

Application filed June 24, 1908. Serial No. 440,200. Term of patent 7 years.

To all whom it may concern:

Be it known that I, WALTER J. FROST, a resident of the United States, residing at Kenosha, in the county of Kenosha and State of Wisconsin, have invented a new, original, and ornamental Design for Traps for Waste-Water Pipes, of which the following is a specification, reference being had to the accompanying drawing, forming part thereof.

In the drawing Figure 1 is a side elevation of a trap for waste water pipes showing my new design. Fig. 2 is a front end elevation of the same.

Describing this design it consists essentially of a bulbous, spherical trap chamber having inlet and outlet pipe stubs. The bulbous trap chamber comprises upper and

lower hemispherical members conveniently united by a circumferential and horizontally extending bead joint. The inlet and outlet pipe stubs are arranged to rise with their axes parallel with each other and disposed at diametrically opposed sides of the upper hemisphere. One of these upstanding pipe stubs or nipples is shown with an attached limb or pipe extension.

I claim:

The ornamental design for a trap for waste water pipes, as shown and described.

WALTER J. FROST.
